UNITED STATES PATENT OFFICE.

MARK THOMAS DENNE, OF RUSHDEN, ENGLAND.

BLANK-FEED MECHANISM FOR HEEL-COMPRESSING MACHINES.

1,238,391.

Specification of Letters Patent. Patented Aug. 28, 1917.

Application filed October 18, 1913. Serial No. 796,063.

To all whom it may concern:

Be it known that I, MARK THOMAS DENNE, a subject of the King of Great Britain and Ireland, residing at Rushden, Northamptonshire, England, have invented new and useful Improved Blank-Feed Mechanism for Heel-Compressing Machines, of which the following is a specification.

This invention has reference to an improved blank feed-mechanism for heel compressing machines, and is intended for use on heel compressing machines having a swinging or rocking table or die carrier, for example, such as is described in the specification of my United States Letters Patent No. 1,176,743, dated March 28, 1916, although I do not limit the application of my invention thereto.

In the machine described by way of example in said patent, the table or die carrier, in addition to swinging or rocking movements, has vertical movements imparted to it. When my present invention is to be applied to such a machine I prefer to support the operating parts of the blank feed mechanism on a vertically movable part of such machine—say by a bracket—so that they will move vertically up and down therewith but will not rock or swing with the table or die carrier.

A feature of my improved feed-mechanism is that a pair of feed-arms is made to carry or move a heel blank into position on the table or the heel seat die thereon when the table is tilted outward the said arms retaining the blank in position while the table begins to move to the heel compressing position and thereafter will permit the table to force them apart when nearing the end of its swinging movement. Another feature is that the feed arms are made to move in such a path—angular to the path of movement of the swinging table—that at one end of their path of movement the attendant may insert a blank by merely pushing it directly between their free ends and against a guide rail which is parallel or substantially parallel to the said path of movement. Other features of my invention are comprised in the particular path of movement which I preferably impart to the arms and also in the improved mechanism whereby the movements of the several parts are attained, all to be hereinafter described.

In the accompanying drawing I have illustrated—by way of example—a form of construction of my invention as it may be applied to the heel compressing machine which forms the subject-matter of my said Letters Patent No. 1,176,743, and so far as I have in this specification illustrated parts of the said heel compressing machine I have adopted similar numerals of reference.

In the accompanying drawing, Figure 1 is a plan view of a constructional form of my invention and Fig. 2 shows that form applied to my particular heel compressing machine referred to.

At a position closely adjacent to the table 18 and preferably supported by one of the bearings 4 carrying the shaft 5 of said machine I provide an inclined platform 50 the angle of inclination of which is about coincident with the angle of inclination of the said table 18 when the latter is at its most outward or tilted position and which platform—for example by being carried on an arm or the like 51 having a spindle 52 slidable in a bearing 53 and adapted to be clamped by a set screw 54—may be set up or down accordingly as a very convex or comparatively flat heel seat die is carried on the table. Said platform is provided with a rail or guide 50^a to be referred to.

At one side of the platform 50 and at right angles thereto—and at a position about opposite or in front of the table 18 of my said machine—I provide a spindle 55 the upper end of which carries a boss 61 adjustably secured to said spindle. The boss carries at diametrically opposite sides a pair of brackets 58, 59 the former to support a set screw 58^a and the latter a spring device 59^a between which a bar 60 having rack teeth on its opposite longitudinal sides is slidably supported. The spring device 59^a serves to press the bar 60 toward or against the set screw 58^a—the latter acting as an adjustable stop—and the force of the spring device may be adjusted or regulated by any well known means as a set screw 59^b.

Also carried on the boss 61 are a pair of spindles 56, 57 one on each side of and at equal distances from the rack bar 60 on which spindles arms 62, 63 are respectively rotatably mounted. The boss of each said arms is formed or provided with a segmental rack to engage the relative rack 110

teeth of the bar 60 and by the action of the spring device 59^a pressing the bar 60 toward the stop 58^a it will be understood the front ends of the arms 62, 63 will be brought together to a greater or less extent dependent upon the position or adjustment for the time being of the set screw or stop 58^a and further by the particular means described both arms must move to the same extent 10 either toward or from each other.

The free end of each of the arms is provided with a roller or equivalent the shape of which will preferably correspond to the shape of the heel blanks to be fed.

15 The shaft 55 is carried in a suitable bearing and at its lower end is provided with a spur wheel 55^a gearing with another such wheel 55^b which latter is made to oscillate at the proper times from a suitable moving 20 part of the machine the arrangement being such that when the table 18 is in its heel-compressing position the shaft 55 will rotate and the arms 62, 63 will be thereby swung over the platform 50 (to a position 25 at about right angles to that shown in Fig. 1) and at this time the operator or attendant feeds a heel by pressing the latter between the rollers 64 and up against the rail 50^a the rollers closing in on the heel. There- 30 after the shaft 55^a is made to rotate to cause the arms 62, 63 to sweep or move the heel on to the table 18 (or the die carried thereby) as shown in plan view, it being understood that the table has meanwhile been 35 returned to its lowermost position.

After the arms have positioned the heel over or on the table 18 the latter is made to swing (in the manner described in my above-mentioned patent) and in doing so 40 will carry the heel with it. During this swinging movement of the table, the portion 19 thereof will engage the rollers on the arms 62, 63, thus separating them to permit the table to have the above-described 45 movement, the spring 59^a yielding to permit such movement of the arms. When the table 18 is clear of the arms 62, 63, said arms will be automatically swung into their heel-receiving position by the expanding action 50 of the spring 59^a.

When the table again swings into the position shown in Fig. 2 it will, of course, carry the lastly compressed heel and the arm 62 or its roller will knock such heel off 55 into a basket or receptacle provided therefor while placing another heel thereon.

What I claim as my invention and desire to secure by Letters Patent is:—

1. In a heel compressing machine, the combination of a swinging table, a heel blank feeding mechanism comprising spring-pressed blank gripping means movable in a plane angular to the plane in which the table rocks or swings, and means for moving the said gripping means into position to receive 65 a heel blank while the table is in its heel compressing position and into position to transfer the heel blank on to the table when the said table is swung out to its heel blank receiving position.

70 2. In a heel compressing machine, the combination of a swinging table and a heel blank feeding mechanism adapted to swing in a plane angular to that in which the table swings and comprising a rotatable carrier, 75 a pair of heel gripping arms pivotally mounted at diametrically opposite points on the said carrier, a segmental rack formed on the boss of each arm concentric with its pivot, a rack bar mounted on the carrier to 80 slide tangentially to and between the pivots of the said arms and formed with teeth at its opposite sides to gear with the aforesaid segmental racks, a spring acting upon one end of the said rack bar and tending to 85 cause it to rotate the said arms to bring their free ends toward each other, and an adjustable stop acting upon the other end of the said rack bar to limit the action of the 90 said spring.

3. In a heel compressing machine the combination of a swinging table, a heel blank feeding mechanism comprising pivoted spring-pressed arms geared together and adapted to swing in a plane angular to that 95 in which the table rocks or swings, means for moving the said arms into position to receive a heel blank while the table is in its heel compressing position and into position to transfer the heel blank on to the 100 table when the said table has swung out to its heel blank receiving position, and a stationary guide rail arranged concentric with the path of movement of the said arms.

105 In testimony whereof I have signed my name to this specification in the presence of two subscribing witnesses.

MARK THOMAS DENNE.
